UNITED STATES PATENT OFFICE.

ORSON N. KELLY, OF DALLAS, TEXAS.

RAILWAY-TIE.

1,034,623.

Specification of Letters Patent.

Patented Aug. 6, 1912.

Application filed May 6, 1911. Serial No. 625,461.

To all whom it may concern:

Be it known that I, ORSON N. KELLY, a citizen of the United States, residing at Dallas, in the county of Dallas and State of

5 Texas, have invented certain new and useful Improvements in Railway-Ties, of which the following is a specification, reference being had to the accompanying drawings.

This invention is an improved channelled 10 metallic railway tie combined with wooden blocks for supporting the rails and improved devices for fastening the blocks in the tie and the rails on the blocks, the invention consisting in the construction, combination and arrangement of devices herein- 15 after described and claimed.

In the accompanying drawings—Figure 1 is partly an elevation and partly a longitudinal sectional view of a railway tie embodying my improvements and showing the same in connection with a pair of rails supported on the tie; Fig. 2 is a transverse sectional view of the same; and Figs. 3 and 4 are detailed longitudinal sectional views 25 showing modified forms of my invention.

The tie 1 is made of iron or steel and is channel shaped, comprising a bottom 2 and side walls 3. The tie is provided in its bottom, preferably at a central point, with 30 an opening 4 for draining water from the tie and at opposite sides of the opening are down-turned anchoring flanges 5 which are integral with the bottom of the tie and are formed by down-turned portions thereof.

35 At the ends of the tie the said walls are cut vertically as at 6 to form portions 7 which are turned downwardly and become embedded in the road bed and serve to firmly secure the tie against transverse movement.

40 on the road bed, the flanges 5 securing the tie against endwise movement. The bottom of the tie is also provided, near its ends, with up-turned flanges 8 which bear against the outer ends of the wooden blocks 9 which

45 support the rails 10 and are placed in the tie. The upper surfaces of the blocks are somewhat above the side walls of the tie. A transverse securing bolt 10^a extends through each block 9 and also through the side walls 50 of the tie. Hence, the blocks are firmly secured in the tie and reinforce and strengthen the tie as well as serving to support the rails and to insulate the rails from the tie, the blocks, which are of wood, being non-conductors of electricity. The up-turned flanges 8 which bear against the outer ends

of the blocks help to support the blocks in place on the tie and relieve the bolts 10^a of side stress as will be understood.

The rails, which bear and are supported on the blocks have their base flanges engaged on opposite sides by flanged inwardly extending projections 11 with which clamps 12 are provided, the said clamps bearing directly on the block and their engaging flanges overhanging and bearing on the base flanges of the rails. These clamps are provided with central openings and the blocks are also provided with openings 13 which are coincident with those of the clamps and the lower ends of which are enlarged and counter-sunk as at 14. Bolts 15 extend up through the openings in the blocks and clamps and have their heads 16 disposed in counter-sinks 14 and bearing against the upper sides thereof so that the heads of the bolts as well as the shanks of the bolts are entirely out of contact with the tie. Nuts 17 are secured on the upper ends of the bolts and bear on the clamps and secure the latter 80 and, hence, also the rails in place on the blocks.

It will be understood that since the blocks are insulators and project above the side walls of the tie and since the bolts which, in connection with the clamps, secure the rails on the blocks have their lower portions embedded in the blocks, and together with the clamps, are thus held by the blocks entirely out of contact with the tie, the rails are completely insulated from the tie as is required when the rails are employed as return conductors in electric block signaling and other signaling systems.

In the modification shown in Fig. 3 the 95 bolts 18, which secure the clamps 19 on the blocks 20, pass through the bottom of the tie as well as through the blocks and the clamps, the heads 21, at the lower ends of the bolts bearing directly against the bottom of the tie. In this form of the invention the bolts not only secure the clamps and hence also the rails on the blocks, but also greatly assist in securing the blocks in and to the tie.

100 In the modification shown in Fig. 4 the rails are secured on the blocks 22 by oppositely inclined screw spikes 23 which are provided with clamping heads 24 that have flanges 25 to bear on the base flanges of the 110 rails. These screw spikes are driven in the blocks and their length is less than the ver-

tical extent of the blocks so that the screw shanks become embedded in the blocks and are entirely out of contact with the tie and hence the rails are completely insulated from the tie.

Having thus described my invention I claim:

1. A metallic railway tie, comprising a channeled body portion with a bottom and 10 upwardly projecting side walls, the bottom being formed intermediate of the ends of the tie with a drain opening and the end walls of said drain opening being turned down to form intermediate anchoring flanges, 15 end portions of the sides being turned downwardly below the bottom to form end anchoring members, and the ends of the bottom intermediate said end anchoring members being turned upwardly substantially 20 at right angles to the bottom, whereby to serve as end braces for insulating blocks.

2. A railway tie of the character described, including a metallic body portion having a bottom and side walls, the end 25 portions of the side walls being turned down below the bottom to form end anchoring members, and the ends of the bottom between said anchoring members being turned upwardly at right angles to the bottom and

lying between the side walls, and blocks 30 mounted in between the side walls and resting upon the bottom and abutting at their outer ends against the upturned ends of the bottom.

3. A railway tie of the character described, comprising a channeled body portion with a bottom and upwardly projecting side walls, the bottom being formed intermediate of the ends of the tie with a drain opening and the end walls of said drain 40 opening being projected downward to form intermediate anchoring flanges, the end portions of the bottom intermediate of said end anchoring members being turned upward, blocks mounted in the body portion and extending 45 above the upper edges of the side walls thereof and engaging the upturned end portions of the bottom and means for securing the blocks in place in the body portion, and means adapted to secure rails to 50 the blocks, as set forth.

In testimony whereof I hereunto affix my signature in the presence of two witnesses.

ORSON N. KELLY.
